Inventor:

Leonhard Becker
By *Samuel Gruelke*
Attorney.

UNITED STATES PATENT OFFICE.

LEONHARD BECKER, OF WIESBADEN, GERMANY.

VAPORIZER FOR INTERNAL-COMBUSTION ENGINES.

Application filed February 1, 1924. Serial No. 690,012.

To all whom it may concern:

Be it known that I, LEONHARD BECKER, a citizen of the German Republic, and resident of Wiesbaden, Germany, have invented 5 certain new and useful Improvements in Vaporizers for Internal-Combustion Engines, of which the following is a specification.

This invention relates to improvements in 10 atomizing or vaporizing the fuel in internal combustion engines; and it comprises a device for simply and thoroughly atomizing or vaporizing the fuel, whereby a complete combustion of the gases is ensured. Essentially 15 the invention consists in utilizing the principle of the reaction wheel, as for instance, used in water sprayers in the irrigation of gardens. In carrying out this principle a wheel or rotatable body is set in rotation by the reaction of the working medium 20 issuing in fine jets, whereby owing to the rotation and the spraying tubes the working medium is atomized to the highest extent possible.

25 The accompanying drawing illustrates by way of example a suitable apparatus embodying the invention. In the drawing:—

Figure 1 is a cross-section through the improved vaporizing apparatus, and

30 Figure 2 is a plan of the reaction or nozzle wheel.

The same letters of reference indicate similar parts in both figures.

The improved vaporizer is located between 35 the carburetor and the motor, and is preferably attached to the former in some suitable way—for instance, by means of the lower flange on its case *k*, so that the gaseous mixture will pass from the carburetor into 40 the vaporizer through the central opening *e* in said flange, said opening having mounted in it a bearing piece or spider *f*. On entering the vaporizer, the gaseous mixture will pass directly into the interior of a rotating 45 body or wheel *b*, provided at its upper part with a peripheral series of bent spraying tubes *a*, and will produce a reaction which sets the wheel body *b* in rotation in the opposite direction to the direction in which the 50 tube openings point; said body being fixed to a vertical shaft *g* which is mounted at one end in the bearing in spider *f*, and at its other end in a similar bearing piece or spider

h mounted in the upper or outlet opening *i* in the top of the vaporizer case. The tubes *a* produce an extremely fine drizzling rain or mist as in garden sprayers, and split up the gas or the gas mixture into minutest particles to which particles they impart a very high velocity. In this manner an intimate mixture of the gas with the air is obtained. The high velocity and the minuteness of the particles prevent, furthermore, the formation of drops. This latter feature is of very great importance inasmuch as the formation of drops prevents complete combustion, particularly when heavy oils are employed, and thus constitutes the cause of the disagreeable smoke development. By means of the nozzle *c* located in the lower part of the 70 casing, cold air if needed may be added to the mixture. Heating of the working medium is not necessary as extensive experiments have proved that the process brings about a perfect mixture and extremely fine 75 atomization. From this it follows that when a cold gas mixture is employed the best imaginable volumetric efficiency of the exploding mixture is obtained. For the purpose of thoroughly stirring the gas-air mixture prior to its entrance into the reaction wheel, an auxiliary impeller or fan *d* is provided and is secured to the shaft *g* within the wheel body.

It will be readily understood that changes 85 may be made within the scope of the invention as recited in the appended claim.

What I claim as my invention and desire to secure by Letters Patent is:—

A vaporizer for internal combustion engines, comprising a case having an inlet for communication with the carburetor of the engine to receive the gaseous mixture therefrom, and also having an outlet opening for communication with the engine intake to deliver the vaporized mixture thereto; a vertical shaft in said case supported in at least one of said openings; a hollow body carried by said shaft and having an open inlet end which is disposed immediately opposite and adjacent to the inlet opening in the case, to permit the gaseous mixture entering said case to pass directly into said body; and a series of bent spraying tubes attached to the periphery of said body and through which the mixture is adapted to flow, whereby said

body will be automatically rotated at high speed solely by the reaction of the mixture on said tubes during its passage therethrough, and said mixture will be discharged from the tubes in the form of an extremely fine mist.

In testimony whereof I have signed my

name to this specification in the presence of two subscribing witnesses, at Stuttgart, January 11, 1924.

LEONHARD BECKER.
